UNITED STATES PATENT OFFICE.

EDWIN B. JENNINGS, OF NEW YORK, N. Y.

SHELL-DAM.

No. 878,960.

Specification of Letters Patent.

Patented Feb. 11, 1902.

Application filed October 21, 1907. Serial No. 398,356.

To all whom it may concern:

Be it known that I, EDWIN B. JENNINGS, a citizen of the United States, residing at the borough of Manhattan, in the city, county, and State of New York, have invented an Improvement in Shell-Dams, of which the following is a specification.

My invention relates to an improvement in shell or hollow dams of simple or reinforced concrete, and the object of my invention is the production of a shell dam using a minimum amount of material and having a maximum degree of strength, rigidity and stability.

According to my present invention my improved dam is arched and of substantially semi-elliptical form in cross section at the lower part, which imparts to the said lower part an extended base or broad support.

This lower part is provided with an upper part forming a rising extension thereof and the surface of the lower part and this upper portion on the side of the impounded water is substantially an ogee curve, the upper limb of which comes over and above the upper part of the arch, thus throwing the weight of the impounded water for nearly half its depth upon the upper and stronger part of the arch tending to firmly seat the same to its bed while the thrust of the impounded water tending to un-seat the dam has this weight as an off-set; this thrust upon the upper limb of the ogee curve pulling from the lower or foundation end of this ogee curve.

The down stream wall or apron of the dam is inclined and curved slightly but is sufficiently straight to constitute a strut having a direct thrust strain applied thereto—by the impounded water—to the foundations thereof.

The details of the foundation for my improved shell dam and the internal construction thereof form no part of my present invention.

In the drawing, Figures 1 and 2 are vertical sections representing forms of my invention.

a represents the rock or earth bed prepared to receive suitable foundations *b*, and *c* represents the semi-elliptical wall of my improved shell or hollow dam of concrete, of any desired dimensions. The ends of the semi-elliptical wall therefore rest upon the independent footings or foundations *b*.

Referring particularly to Fig. 1, I build

upon this semi-elliptical wall an upper portion, extension or prolongation *d* having an opening *d*¹ therein for the purpose of reducing the weight and material. The outer surface 2 of this wall and the upper portion *d* on the up-stream side against which the impounded water bears is an ogee curve, the convex member of which is the outer surface of the wall *c* and the concave member of which is the outer surface of the extension or upper portion *d*. This concave portion or upper limb is continued out from the convex portion near the upper part of the wall *c*, starting at slightly above half the depth of the impounded water; therefore the said shell dam on the inner surface receives an appreciable amount of the weight of the impounded water, tending to firmly seat the same to its bed, while the thrust of the impounded water tending to lift the dam off the seat must of necessity tend to lift this weight of water and to pull the curved member of the dam from its foundation at the same time the outer slightly curved but almost straight surface of the dam forms a strut in the integral structure, tending with this movement to force the outer portion of the dam more firmly to its foundation. Thus the various strains tend to compensate one another so that the dam maintains its position carrying the weight and pressure of water behind them or on the up-stream side.

The opening *d*¹ in the upper member *d* is simply to reduce the weight of the shell or hollow dam and the amount of materials employed.

The form of my invention shown in Fig. 1 is not only suitable for the full length of a dam but may also be employed as a structure for the spill-way part of the dam, as the outer surface is eminently fitted for the delivery of surplus water.

Referring to Fig. 2, the description hereinbefore made with reference to Fig. 1, answers essentially for the form of my invention shown in Fig. 2, except that in Fig. 2 the upper extension *e* from the semi-elliptical wall *c* is thrown forward toward the down-stream side of the dam; thus bringing even more of the weight of the impounded water upon the dam structure, tending to hold it down in position; the ogee curved surface 3 of this form of my invention being more pronounced even than that in Fig. 1, but the outer or down-stream wall or apron while suitable for

the main portion of the dam would not be quite as suitable for the spill-way portion, as the same is slightly too vertical.

I claim as my invention:

5 1. A hollow or shell dam of concrete comprising a semi-elliptical wall, resting by independent footing upon a suitable foundation and a rising portion or extension from the upper part thereof.

10 2. A hollow or shell dam of concrete comprising a semi-elliptical wall, suitable foundations therefor, a rising portion or extension from the upper part thereof, said extension being of hollow construction and the up-
15 stream surface of the hollow dam being an ogee curve.

3. A hollow or shell dam of concrete comprising a semi-elliptical wall, suitable foundations therefor, a rising portion or extension

20 from the upper part thereof, said extension being of hollow construction and the up-

stream surface of the hollow dam being an ogee curve and the down-stream wall or apron forming a strut having a direct thrust strain applied thereto by the impounded 25 water.

4. A hollow or shell dam of concrete comprising a semi-elliptical wall, suitable foundations therefor, a rising portion or extension from the upper part thereof and which extension is formed integrally with the semi-elliptical wall and mainly to one side of the vertical center of said wall on the down-
30 stream side so that the weight of an appreciable depth of the impounded water rests 35 upon the semi-elliptical wall.

Signed by me this 14th day of October
1907.

EDWIN B. JENNINGS.
